UNITED STATES PATENT OFFICE.

JACOB H. WILT, OF TOLEDO, OHIO.

ROPE-SOCKET FOR WELL-TOOLS.

1,192,252.

Specification of Letters Patent. Patented July 25, 1916.

Application filed November 27, 1915. Serial No. 63,862.

To all whom it may concern:

Be it known that I, JACOB H. WILT, a citizen of the United States, residing at Toledo, in the county of Lucas and State of Ohio, 5 have invented new and useful Improvements in Rope-Sockets for Well-Tools, of which the following is a specification.

This invention relates to a rope socket for well tools of the class commonly termed 10 a jar rope socket and swivel plunger, which may be used to connect a drill rope with a well tool.

The primary object of the invention is to provide a rope socket of the class described 15 which, when applied to a well tool may be used to connect either a Manila drill cable, or a wire cable, with the well tool.

Another object of the invention is to provide 20 a device of the class described in which a plunger may be retained in the tool holder, or a rope socket retained in the plunger, without using threaded couplings, bolts or the like, thus avoiding any possibility of 25 the parts becoming disconnected while the device is in use.

A further object of the invention is to provide the rope socket with a swivel plunger which normally serves as a socket for 30 the Manila cable and has a centrally disposed bore therein, in which may be removably mounted a socket member, for the reception of a wire cable thus adapting the device for use in connection with either a 35 Manila drill cable, or wire cable as the occasion may require.

A still further object of the invention is to provide the tool holder which serves as a casing for the swivel plunger with novel 40 means for retaining the plunger within the tool holder, said means coacting with the sleeve to limit the sliding movement of the plunger within the tool holder in one direction.

Another object of the invention is to provide 45 a plunger for the device having a centrally disposed bore therein which coacts with a reduced portion on the socket member for connection with a wire rope, to provide 50 a chamber within the plunger for the reception of fusible material, for holding the socket member within the plunger, so that the socket member may be removed

from the plunger when the occasion requires without the necessity of removing the plunger 55 from the tool holder.

With these and other objects in view the invention resides in the novel combination and arrangement of parts which will be hereinafter described and more particularly 60 pointed out in the claims.

The preferred embodiment of the invention has been illustrated in the accompanying drawings, although no restriction is necessarily made to the precise details of 65 construction therein shown, as changes, alterations and modifications within the scope of the appended claims may be resorted to when so desired.

Like characters of reference denote corresponding 70 parts throughout the several views in the drawings in which,

Figure 1 is a side elevation of a rope socket for well tools constructed in accordance with the invention, Fig. 2 is a vertical 75 transverse sectional view taken on the line 2-2 of Fig. 1, Fig. 3 is a view similar to Fig. 2 showing the socket member for engagement with a wire cable removed from the plunger of the device and a portion of 80 a Manila drill cable secured in said plunger, Fig. 4 is a horizontal transverse sectional view on the line 4-4 of Fig. 2, Fig. 5 is a view similar to Fig. 4 taken on the line 5-5 of Fig. 2, Fig. 6 is a sectional view taken on 85 the line 6-6 of Fig. 3.

Referring now to the drawings in detail the numeral 1 designates the rope socket as a whole which, comprises a casing or tool holder 2 in which is mounted a plunger 3 90 adapted for the reception of a socket member 4.

The tool holder 2 which is cylindrical in shape is provided at one end with a threaded opening 5 adapted to receive a well tool 95 not shown in the drawings. The tool holder 2 has extending centrally thereof for the greater portion of its length a bore 6, said bore being enlarged for a portion of its length adjacent the upper end of the tool 100 holder, as indicated at 7 to provide a shoulder 8. The enlarged portion 7 of the bore 6 is provided on its inner peripheral surface above the shoulder 8 with circular corrugations 9 for a purpose which will be 105 hereinafter described. The bore 6 has a

portion thereof adjacent its lower end reduced, as indicated by the numeral 10 to provide a seat 11. Arranged at diametrically opposite points in the tool holder 2 above and below the reduced or enlarged portion of the bore 6 are openings 12, which, coact with similar openings 13 communicating with the reduced portion of the bore 6 at the lower end thereof to provide inlet 10 and outlet ports for fluid or other foreign matter which may gain access to the interior of the bore 6 while the tool holder is in use. An opening 14 is formed in the tool holder 2 and communicates with the interior of the bore 6 between the enlarged and reduced portion thereof.

Mounted in the bore 6 of the tool holder 2 for sliding and rotary movement is the plunger 3, said plunger having an enlarged portion 15 between the ends thereof of less length than the distance between the enlarged portion 7 and the reduced portion 10 of the bore, said enlargement providing shoulders 15' and 16 on the plunger 3. The plunger 3 is also provided with a centrally disposed bore 17 enlarged between the ends, as indicated by the numeral 18 and has communicating therewith an opening 19 opening out through the peripheral wall of the plunger 3.

A sleeve 20 is disposed in the enlarged portion of the bore 6 and has one end thereof resting upon the shoulder 8 to limit the downward movement of the sleeve within the bore 6. The sleeve 20 is provided with an annular beveled portion adjacent the portion thereof adapted to contact with the shoulder 8 as indicated by the numeral 21, said beveled portion providing a seat against which the shoulder 16 on the plunger is adapted contact upon upward movement of the plunger within the tool holder. The upper portion of the sleeve 20, is reduced and provided with circular corrugations 22 similar to the corrugations 9 and registering therewith to provide a chamber 23 in the upper portion of the tool holder 2 for the reception of suitable fusible material, indicated by the numeral 24. Threadedly engaged with the upper end of the tool holder 2 and inclosing the open end of the chamber 23 is a cap 25, said cap having a centrally disposed opening 26 through which loosely passes one end of the plunger 3, while arranged concentrically about said opening and communicating with the chamber 23 are openings 27.

Disposed in the bore 17 in the plunger 3 is the socket member 4, said socket member 60 being provided with a centrally disposed channel 28 having a flared portion 29 at the lower end of said channel to receive the knotted end of the wire cable when passed therethrough. The socket member 4 is reduced between its ends, as indicated by the

numeral 30, said reduced portion being adapted to register with the enlargement 18 in the bore 17 and coact therewith to provide a chamber for the reception of fusible material for maintaining the socket member 70 within the plunger 3 as indicated by the numeral 31.

Referring now to Fig. 3 in the drawing it will be seen that when the rope socket and swivel plunger are used to connect the end of the Manila drill cable with the well tool the cable can be disconnected from the rope socket in the following manner: The plunger 3 is first moved in an upward direction till the shoulder 16 contacts with the seat 21 on the sleeve 20. With the plunger in this position the bolt or pin 32 is passed through the openings 13 and through notches 33 in the bottom of the plunger, said bolt holding the plunger in a position to cause the opening 19 therein to register with the opening 14 in the tool holder 2. The knotted end of the Manila drill cable can now be withdrawn from the enlarged portion 18 of the bore 17 through the openings 19 and 14 sufficiently far to enable the knot to be untied, whereupon movement in one direction of the tool holder or cable will cause the end of the cable to be withdrawn from the bore in the plunger. It will of course be understood that when it is desired to connect the Manila drill cable with the tool holder the above mentioned operation is reversed and that when the bolt 32 has been withdrawn from the tool holder the device is ready 100 for use.

If for any reason it should be necessary to remove the plunger with the end of the Manila drill cable the end of the tool holder containing the fusible material is heated 105 and held in a position to enable said material to escape through the openings 27 in the cap 25 while in a molten state. After this has been accomplished the cap 25 may be removed from the end of the tool holder 110 and the plunger to which the drill cable is attached removed therefrom.

When it is desired to connect the end of the wire drill cable with the tool holder the end of the Manila cable is removed from the 115 plunger in the manner first described and the end of the wire cable passed through the socket member 4 and knotted. The socket member is now positioned in the plunger and fusible material poured through the 120 openings 14 and 19 into the tool holder till the chamber formed by the enlargements of the bore in the plunger and the reduced portions in the socket member is filled as clearly illustrated in Fig. 2 in the drawings. 125

From the foregoing statement it will be seen that the socket member will be securely held within the plunger and that when it is necessary to remove the socket member from the plunger the heat applied to the tool 130

holder will soften the fusible material 31 and allow the same to escape through the openings 14 and 19.

From the above described construction it 5 will be at once apparent that the socket member can at any time be removed from the plunger without disconnecting the plunger from the tool holder thus adapting the device to be advantageously used in connection with either a wire drill cable or a 10 Manila drill cable as occasion may require.

Having thus described the invention what is claimed as new is:

1. A device of the class described, comprising a casing having a longitudinally extending bore, a sleeve removably mounted in said bore, means for retaining the sleeve within the casing disposed between said sleeve and casing, a plunger mounted to 15 slide and turn in said bore and sleeve and having a centrally disposed channel, and a socket member removably mounted in said plunger.

2. A device of the class described comprising a casing having a longitudinally extending bore, a plunger mounted to turn and slide in said bore, a sleeve disposed in said bore for limiting the sliding movement of said plunger in one direction, fusible material interposed between said sleeve and casing, a socket member disposed in said plunger and provided with a centrally arranged channel providing a rope socket, and means for retaining the socket member 30 within the plunger.

3. A device of the class described comprising a casing having a longitudinally extending bore, a plunger mounted to turn and slide in said bore, a shoulder formed in 35 said bore for limiting the sliding movement of the plunger in one direction, a sleeve disposed in the path of movement of the plunger above said shoulder and removably connected with the casing, a socket member 40 extending longitudinally of the plunger and provided with a reduced portion, and means

for retaining said socket member within the plunger interposed between the reduced portion on the socket member and the plunger.

4. A device of the class described comprising a casing having a longitudinally extending bore, said bore being enlarged and corrugated for a portion of its length, a plunger mounted to turn and slide in said bore having a reduced end extending 50 through said enlarged portion, a sleeve encircling the reduced end of said plunger and disposed in the enlarged portion of said bore, a reduced portion on said sleeve provided with corrugations adapted to register 55 with the corrugations in the enlarged portion of the bore and in spaced relation therewith, fusible material interposed between the reduced portion of the sleeve and the corrugated portion of the bore, a cap threadedly engaged with the tool holder and having a portion thereof overlying the fusible material and provided with openings, and a socket member carried by said plunger.

5. A device of the class described comprising a casing having a longitudinally extending bore and an opening communicating with the bore between the ends thereof, a plunger mounted to slide and turn in said bore and provided with a centrally disposed channel extending throughout its length, said channel having an enlarged portion between its ends and an opening communicating with the enlarged portion through the side wall of the plunger, and a 60 socket member disposed in the channel of the plunger and having a reduced portion between its ends coacting with the enlarged portion of the channel in the plunger to provide a chamber adapted to receive fusible material.

In testimony whereof I affix my signature in presence of two witnesses.

JACOB H. WILT.
